Primary Examiner — Karen E Kearney*Assistant Examiner* — Amber R Lee(74) *Attorney, Agent, or Firm* — Lucian Wayne Beavers; Andrew T. Ball; Patterson Intellectual Property Law, PC(57) **CLAIM**

The ornamental design for an individual shelf as shown and described.

DESCRIPTION

FIG. 1 is a front perspective view showing the individual shelf of applicant's invention.

FIG. 2 is a front view of the individual shelf of applicant's invention, front and back being identical.

FIG. 3 is a left side view of the individual shelf of applicant's invention, both sides being identical.

FIG. 4 is a top view of the individual shelf of applicant's invention; and,

FIG. 5 is a bottom view of the individual shelf of applicant's invention.

As used in this disclosure, elements indicated with broken or dashed lines represent subject matter that forms no part of the claimed design.

1 Claim, 4 Drawing Sheets(56)
